(57) **CLAIM**

The ornamental design for an irrigation stake as shown and described.

DESCRIPTION

FIG. 1 is a top perspective view of an irrigation stake.

FIG. 2 is a right side view of an irrigation stake.

FIG. 3 is a left side view of an irrigation stake.

FIG. 4 is a rear view of an irrigation stake.

FIG. 5 is a front side of an irrigation stake.

FIG. 6 is a top view of an irrigation stake.

FIG. 7 is a bottom view of an irrigation stake; and,

FIG. 8 is a side perspective view of an irrigation stake, in use.

The regular broken lines illustrate a ratchet for driving the irrigation stake and a line clip and are not part of the claim.
